(57) **CLAIM**

The ornamental design for an abutment for denture implant as shown and described.

DESCRIPTION

FIG. 1 is a perspective view of an abutment for denture implant showing my design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is another perspective view thereof; and,

FIG. 9 is a sectional view along line 9-9 in FIG. 4.

The dash-dash broken lines shown in the drawings represent portions of the abutment for denture implant that form no part of the claimed design. The dot-dash broken lines shown in FIG. 4 are included to represent the indication of the cross-sectional view and form no part of the claimed design.
